DAVID H. ZELL, OF BROOKLYN, NEW YORK

DECORATIVE COVERING FOR VANITY CASES, COIN BANKS, AND OTHER RECEPTACLES

Application filed April 25, 1929. Serial No. 357,891.

This invention relates to decorative coverings for vanity cases, coin banks and other receptacles of the type wherein the receptacle is provided with a side wall or closure 5 hingedly mounted upon one of the body walls of the receptacle.

It is the primary object and purpose of the invention to provide means whereby in the opening movement of the hinged wall or closure, the flexible decorative covering material thereon which extends around the edge of the receptacle body will be prevented from bulging or buckling, thereby obviating excessive strains upon such material at the hinge 15 joint tending to severely crease or crack the surface of the material, and thus mar or detract from the ornamental appearance of the article.

In one practical embodiment of my invention, I provide separate sheets of the flexible covering material such as leather cemented or otherwise securely fixed to the outer faces of one side wall of the receptacle body and to the hinged closure member, and the material on the latter member extending beyond the hinged edge thereof and loosely over the back or rear edge wall of the receptacle body in simulation of the binding of a book. The free edge of this sheet of covering material 20 is extended upon the opposite side of the receptacle and beneath the edge of the covering material thereon and to the same, elastic means is attached. This elastic means automatically operates, as the closure is moved 25 to its open position to draw the unattached portion of the covering sheet thereon around the edge of the receptacle to maintain the same taut and smooth, thus preventing the development therein of wrinkles, creases or 30 cracks.

It is also a further general object of the invention to provide a simple and effective means for the above purpose, which will not add materially to the production cost of such 35 articles as produced under present methods of manufacture.

With the above and other objects in view, the invention consists in the improved ornamental covering for vanity cases, coin banks and other receptacles, as will be hereinafter

more fully described, illustrated in the accompanying drawings, and subsequently incorporated in the subjoined claims.

In the drawing, wherein I have illustrated several simple and practical embodiments of the invention, and in which similar reference characters designate corresponding parts throughout the several views,—

Figure 1 is an edge view of a vanity case or other receptacle provided with my present improvements;

Fig. 2 is a bottom plan view thereof;

Fig. 3 is an enlarged fragmentary sectional view taken on the line 3—3 of Fig. 2, the hinged side or closure for the case being in its closed position and showing one application of my improved ornamental covering material thereto;

Fig. 4 is a similar view showing the hinged closure member in its open position, and

Fig. 5 is a fragmentary sectional view illustrating a slightly modified form of the device.

Referring in detail to the drawing, as will be noted from reference to Figs. 1 and 2 thereof, I have illustrated the invention as applied to a case or receptacle which simulates the general form of a book and in which one of the book covers is represented by the lid or closure for the receptacle. The body of the receptacle generally indicated at 5 may be of any suitable construction, and includes a bottom or side wall surrounded by upstanding marginal walls constituting the front, rear and opposite end edges of the case. Upon the rear body wall 6 of the case, the closure member 7 is hingedly mounted along one of its longitudinal edges as shown at 8. Preferably, the case body and the closure member 7 consists of sheet metal stampings and to the outer surface of the closure plate, a relatively thick sheet of heavy cardboard or other material indicated at 9 may be adhesively attached. A similar sheet of material 10 is also secured to the outer surface of the bottom wall of the case.

To the outer face of the rear wall 6 of the case body, a strip of cardboard or other material extending the full length thereof is secured as shown at 11, said strip having a rounded or convex surface 12 which merges

into a rounded edge of the sheet of material 10 secured to the bottom wall of the case. The material 9 at the hinged edge of the closure member is similarly beveled or rounded as at 13. It will be noted that one edge of the strip 11 is spaced from this hinged edge of the closure member when the latter is in a closed position.

The cardboard or other material 10 on the bottom wall of the case is faced with a sheet of leather or other suitable ornamental covering material shown at 14 smoothly secured thereon by a suitable adhesive. Adjacent to the rear edge of the case in suitably spaced relation to the strip 11, a longitudinally extending narrow slot 15 is formed through the material 10, and at one side of this slot, the inner face of the sheet 10 is beveled as indicated at 16 to provide a longitudinally extending recess of substantial width between the sheet 10 and the bottom or side wall of the case. As shown in Figs. 2 and 3, the edge of the ornamental covering material 14 at this side of the slot 15 projects slightly beyond the edge of the beveled face 16 of the material 10. This projecting edge of the material 14 may be treated with a suitable solution to stiffen the same and is preferably provided with a longitudinally extending groove or corrugation 17.

The material 9 on the closure member 7 is also faced with the flexible ornamental covering sheet 18 which is firmly secured by a suitable cement or adhesive over the entire area 35 thereof, and includes a free or unattached portion 19 extending beyond the hinged edge of the closure member. This portion 19 of the flexible material extends smoothly over the convex surface 12 of the strip 11 and upon the bottom side of the case, the edge thereof being extended through the slot 15 and underlying the edge of the covering sheet 14. To this edge of the part 19 of the covering sheet 18 elastic straps 20 are suitably attached at one 40 of their ends, the other ends of these straps being firmly cemented or otherwise secured to the part 10 of the bottom of the case body.

The edge portion of this part 10, over which the portion 19 of the flexible covering sheet 50 extends, is provided with recesses indicated at 21 adapted to accommodate the ends of the straps 20 when the member 7 is in its closed position, as seen in Fig. 3 of the drawing.

It will be apparent from the above description that while the case is closed, and the straps 20 are elastically elongated or stretched, the part 19 of the flexible covering sheet 18 on the closure member is tightly drawn and held upon the convex surface of 60 the strip 11. The free edge portion of this part 19 of the cover sheet extending through the slot 15 and underlying the edge of the other cover sheet 14, renders inconspicuous the line of demarkation between the two cover sheets and forms what appears to be a de-

pression extending adjacent to the parallel with the groove 17. Thus to the casual observer, these two interruptions in the plane surface of the covering material on the bottom of the case appear as ornamental characteristics of a single continuous cover sheet.

In order to carry out this impression and for purposes of symmetry, the flexible cover sheet 18 on the closure member may also be provided with similarly located parallel 75 channels or grooves 22.

In cases or receptacles of this character as now manufactured, when the cover or closure member is swung to its open position, the flexible covering sheet extending along the back or rear edge of the case bulges outwardly, somewhat in the manner indicated by the dotted lines at 23 in Fig. 4 of the drawings, and in repeated opening and closing of the cover member, the flexible material is severely creased and eventually develops surface cracks along the hinged edge of the cover. Thus this flexible material soon becomes unsightly and detracts from the ornamental appearance of the case. By means of the present improvements however, it will be noted from reference to Fig. 4, that as the lid or closure member of the case is swung to its open position, the elastic straps 20 contract and draw the edge of the part 19 of the cover material on the closure member inwardly through the slot 15 and maintain the same in snug close fitting engagement upon the rounded or convex surface 12 of the edge strip 11. The swinging movement of the closure member to its open position is limited by contact of the edge of the part 9 thereof with the edge of the strip 11 so that said closure member can not be swung beyond a position substantially in parallel relation with the rear edge wall of the case. In this manner, severe flexing or creasing of the ornamental covering material at the hinge line between the movable closure member and the body wall of the case is prevented.

In Fig. 5 of the drawings, I have shown a slightly different form of the invention in which the flexible covering sheet 14' on the bottom of the case, terminates at one edge of the slot 15' formed through the sheet of cardboard or other material 10 at a comparatively sharp inclination, and when the closure member of the case is in its closed position, the free edge of the part 19 of the cover sheet thereon terminates at the opposite edge of said slot. The elastic straps 20 have bearing contact against the opposite edges of the slot at the inner and outer faces of the part 10 and as the closure member is swung to the open position, the walls of the slot provide guides for these bands as they contract so that the edge of the flexible cover sheet 19 will be pulled inwardly into said slot. In this case, it will therefore, be noted that as the edge of the part 19' does

not underlie the edge of the other cover sheet 14' when the case is closed, this slot will be plainly observable. However, I may of course if desired, provide a continuous strip 5 of the elastic material instead of spaced bands and of the same color as the covering sheets so that this material being located in the slot 15' would render the same less conspicuous.

10 From the foregoing description considered in connection with the accompanying drawing, the construction and several advantages of my present invention will be clearly understood. While my improvements are especially designed for use in connection with 15 book form metal vanity cases or coin banks, it will of course be understood that the invention can also be advantageously used in connection with ornamental receptacles employed for various other purposes.

Also, while I have disclosed herein one embodiment of the essential features of the invention, it is to be understood that in practice, the details thereof might be variously modified, while attaining practically the same desirable results. Thus, for instance, other equivalent means than the elastic straps 20 may be provided for the purpose of automatically maintaining the desired smooth snug 25 fitting contact between the flexible cover sheet and the rear wall of the case body during the opening and closing movements of the lid or closure member for the case. It is therefore, to be understood that I reserve the privilege 30 of resorting to all such legitimate changes in the form, proportion and relative arrangement of the several elements as may be fairly incorporated within the spirit and scope of the invention as claimed.

40 I claim:

1. A book form structure including a body having a back or rear edge and a cover member hingedly mounted thereon, an ornamental flexible facing sheet covering the side wall of 45 said body, an ornamental flexible covering sheet secured upon said cover member and having a free portion projecting beyond the hinge line of the cover member and around the rear edge of said body, and means connected with the edge of said free portion of the covering material to maintain the same under tension and in close snug fitting contact with the rear edge of said body during 50 the opening and closing movements of said cover member.

2. A book form structure including a body having a back or rear edge and a cover member hingedly mounted thereon, an ornamental flexible facing sheet covering the side wall of 55 said body, an ornamental flexible covering sheet secured upon said cover member and having a free portion projecting beyond the hinge line of the cover member and around the rear edge of said body, the edge of said 60 free portion of the covering material under-

lying one edge of the facing material on the side of said body, and means attached to said side of the body structure and to said edge of the flexible material on said cover member to maintain the same under tension and in 70 close contact upon the rear edge of the body structure during the opening and closing movements of the cover member.

3. A book form structure including a body having a back or rear edge and a cover member hingedly mounted thereon, an ornamental flexible facing sheet covering the side wall of 75 said body, an ornamental flexible covering sheet secured upon said cover member and having a free portion projecting beyond the hinge line of the cover member and around the rear edge of said body, the edge of said 80 free portion of the covering material underlying one edge of the facing material on the side of said body, and a plurality of elastic straps attached to said side of the body structure and to the free edge of the flexible material on the cover member to maintain the latter under tension and in close contact with the rear edge of said body structure during 85 the opening and closing movements of said cover member.

4. In combination with a book form metallic receptacle consisting of a body structure and a closure member therefor hinged to the rear wall of said body structure, ornamental covering means for said body structure and the closure member consisting of a facing sheet of ornamental material secured upon the side wall of said body structure, a backing strip secured to the outer side of the rear wall of said body structure and having a convex surface, a sheet of ornamental flexible facing material secured upon said closure member and having a free portion extending beyond the hinged edge thereof and over the convex surface of said backing strip, said free portion extending upon the side of said body structure and having its edge underlying an opposed edge of the covering material secured to said side of the body structure, and means for automatically maintaining said free portion of the flexible covering material on said cover member under tension and in tight contact with the convex surface of said 100 backing strip, in the opening and closing movements of said closure member.

In testimony that I claim the foregoing as my invention, I have signed my name hereto.
